UNITED STATES PATENT OFFICE

LEONARD A. RAY, OF CENTER BUTLAND, VERMONT

WINDOW SCREEN

Application filed August 25, 1931. Serial No. 559,281.

This invention has for its object the provision of a window screen which will be automatically drawn across the window opening as the window sash is raised and will be stored 5 in a compact form as the sash is lowered. Another object of the invention is to provide novel connections between the screen and the window sash whereby the screen will follow the movements of the sash and the opening 10 below the sash will always be covered to prevent the entrance of insects. Another object of the invention is to provide means whereby the screen and the connections between the same and the sash will be effectually protected 15 from the weather.

The invention is illustrated in the accompanying drawing and consists in novel features which will be hereinafter first fully described and then more particularly defined 20 in the appended claims:

In the drawing:

Figure 1 is a horizontal section of a window equipped with the present invention,

Figure 2 is a vertical section of the same,

25 Figure 3 is an enlarged detail elevation of a tension device which is employed,

Figure 4 is a section on the line 6—6 of Figure 3,

Figure 5 is a detail elevation of the roller 30 upon which the screen is wound,

Figure 6 is an enlarged detail section on the line 6—6 of Figure 5,

Figure 7 is an enlarged section showing 35 the manner of connecting the screen to the sash.

The window frame 1 may be of the usual or any approved construction and has mounted therein an upper sash 2 and a lower sash 3 which are hung for vertical travel in the 40 usual manner. In carrying out the present invention, a box 4 is secured upon the sill 5 of the window at or near the outer edge thereof and this box is composed of two sheet metal plates of arcuate cross section as shown 45 in Fig. 2 and adapted to overlap at their inner ends, as indicated in Fig. 1, the overlapping section being provided with a longitudinal slot 6 through which a fastening screw 7 is inserted to engage in the over- 50 lapped section and thereby secure them in a

set position. This construction permits the box to be easily adjusted to windows of different widths. At the sides of the window frame similar boxes 8 are provided, these side boxes being secured to the side members of the window frame and having outer webs or portions arranged in diverging relation to the members secured to the window frame and having their lower extremities united 55 with the ends of the box 4 as shown at 9.

The upper ends of the boxes 8 are closed and disposed to abut the upper sash 2 as shown at 10. Extending axially within the box 4 is a roller 11 which is of tubular formation as shown most clearly in Fig. 6 and this tube consists of two members having their meeting ends adjustably or telescopically fitted one within the other as shown at 12 in Fig. 5. Longitudinal slots 13 are formed in 60 the overlapping ends of the tube sections and a fastening bolt 14 is fitted through the registering slots so as to secure the sections of the tube in the position to which they may be adjusted. This construction facilitates the 65 application of the roller to windows of different widths. As shown most clearly in Figs. 5 and 6, the tubular roller is formed with a longitudinal slot 15 extending from end to end thereof. The screen 16 consists 70 of a suitable length of wire netting cloth or like material and one end thereof is fitted through the slot 15 of the roller and then crimped around one wall of the slot as shown at 17, a U-shaped binding strip or clip 18 being then fitted over the crimped portion 75 of the screen and fastening screws 19 inserted therethrough whereby the end of the screen will be firmly secured to the roller. The screen is, of course, wound upon or 80 unwound from the roller as the window sash is lowered or raised and the opposite end edge of the screen is attached to the sash so that it will be controlled by the movements 85 of the sash. To secure the screen to the sash there is provided a clamping bracket 20 which is secured to the lower rail of the sash on the outer side of the same, as shown in Fig. 7, and this clamping bracket is substantially 90 U-shaped in cross section and has one side, web secured to the sash and its parallel 95 side, web secured to the sash and its parallel 100

side web disposed vertically at the outer side of the sash. A clamping strip 21 is engaged over the outer vertically extending side or member of the bracket 20 and this strip 21 is folded or doubled upon itself to provide parallel webs engaging closely over the outer wall of the bracket 20 and present a U-shaped portion at the outer side of said wall. The upper edge of the screen 16 is doubled upon itself and engaged in the outer U-shaped portion of the clamping strip and an anchoring plate 22 is secured upon the lower rail of the sash in such position that it will bear upon the crimp or band of the screen and upon the inner band or crimp of the clamping strip so that the screen will be firmly held in the clamping strip and the clamping strip likewise held firmly upon the bracket 20. The outer edge of the plate 22 may be bent downwardly as shown at 23 whereby the plate will constitute a cover to protect the upper portion of the screen from rain and other elements of the weather.

Upon the ends of the roller 11 are secured grooved pulleys 24 to which are secured the lower ends of the cables 25 which will wind upon and unwind from said pulleys in the operation of the screen. These pulleys are provided upon their outer sides with trunnions 26 whereby they may be journaled in the side boxes and in the side members of the window frame. Guide pulleys 27 are provided in the side boxes 8 a short distance above the respective pulleys 24 and near the grooves in which the sash travels while adjacent the upper ends of the side boxes 8, other guide pulleys 28 are provided. The cables 25 are passed at the rear of the pulleys 27 and then up to the front of the pulleys 28 and over the latter end then down at the rear of the sash, as shown at 29. As the sash moves downwardly, the cables will be unwound from the pulleys 24 and the unwinding of the cables will cause rotation of said pulleys and upon the roller. When the sash is raised a pull is exerted upon the screen which causes the roller and the pulleys 24 to rotate in the opposite direction so that the cables will be wound thereon, the cables and the screen thus acting in opposition so that one may be said to operate the other. The cables are apt to be affected by weather conditions and variations in temperature so that they will tend to stretch at times and at other times will tend to contract. In order to compensate for this stretching and contracting of the cables and maintain them in a taut condition at all times I provide tension devices shown most clearly in Figs. 3 and 4. A plate 30 is slidably fitted against the side wall of each box 8 within the box and the upper guide pulleys 28 are carried by the respective plates 30. These plates are of sheet metal and the roller 11 as well as

the boxes 4 and 8 are also of sheet metal. The plates 30 are held between the angle of the boxes 8 and the edges of the boxes by being engaged under reentrant flanges 31 struck from the side edges of the respective boxes, as shown clearly in Figures 3 and 4. Each plate 30 is formed with a vertically extending slot 32 and a contractile spring 33 has its lower end secured to a lip 34 on the plate 30 and its upper end secured to the side of the box 8 as shown in Figures 3 and 4, the spring being disposed within the slot 32. The spring is normally contracted or closed and consequently yieldably holds the plate 30 at the upper limit of its movement. Should the cables 25 contract, the plates may move downwardly so as to accommodate the contraction and avoid breaking of the cables. When the cables subsequently expand the springs will close and draw the plates 30 upwardly so that the cables will be maintained in the desired taut condition.

From the foregoing description taken in connection with the accompanying drawing, it will be seen that I have provided an exceedingly simple and compact mechanism whereby a screen may be attached to and operated by a window sash and the working parts will be effectually protected from the action of the weather. The screen is located on the outer side of the window so that it will be more conveniently accommodated within the window frame than if it were disposed at the inner side of the window and will leave the window sash free to be raised or lowered easily whenever movement of the sash is desired. The screen may be easily and quickly secured in place without special tools or the use of skilled labor and the sash may be raised to any desired height and the window opening will always be covered by the screen. By being connected directly to the sash, the screen aids in balancing the sash so that it will remain true in the grooves of the window frame.

Having thus described the invention, I claim:

1. In a window screen apparatus having a roller mounted at the lower end of a window frame, a screen attached to said roller to wind thereon or unwind therefrom, means for connecting the screen to a window sash whereby as the sash is raised the screen will be unwound, pulleys secured on the ends of the roller, guide pulleys above said pulleys and arranged at the sides of the window frame, and cables attached to the first mentioned pulleys and wound thereon reversely to the screen and passing upwardly therefrom to and over the guide pulleys and attached to the sash whereby as the sash is lowered the screen will be wound; slidably mounted plates carrying the upper guide pulleys, and springs acting on said plates to hold them normally raised whereby to maintain the cables under tension.

2. In a window screen apparatus, a rolling screen and clamping brackets secured to a window sash and binding the upper edge of the screen whereby the screen will follow
5 the movements of the sash, said clamping brackets comprising a lower member receiving the folded upper edge of the screen and an upper member projecting over the lower member and bearing upon the edge of the
10 screen to hold it in the lower member and having its free edge extending downwardly in front of the upper edge portion of the screen.

3. In a window screen apparatus, a screen,
15 a U-shaped bracket secured to a window sash, a clamping strip engaged with said bracket and having a fold receiving and gripping the upper edge of the screen, and an anchoring plate secured to the window sash and extending therefrom across and bearing upon the upper edges of the clamping strip and the screen.

In testimony whereof I affix my signature.
